US00D837323S

(12) **United States Design Patent** (10) **Patent No.:** **US D837,323 S**
(45) **Date of Patent:** **** Jan. 1, 2019**

(54) **TWO WHEELED BOARD**

(71) Applicant: **RAZOR USA LLC**, Cerritos, CA (US)

(72) Inventor: **Ian Desberg**, Cerritos, CA (US)

(73) Assignee: **RAZOR USA LLC**, Cerritos, CA (US)

(**) Term: **15 Years**

(21) Appl. No.: **29/631,901**

(22) Filed: **Jan. 3, 2018**

(51) LOC (11) Cl. **21-02**

(52) U.S. Cl.

USPC **D21/760**

(58) **Field of Classification Search**

(57) **CLAIM**

The ornamental design for a two wheeled board, as shown and described.

DESCRIPTION

FIG. 1 is a front, top, left-side perspective view of a two wheeled board of our design;

FIG. 2 is a rear, bottom, left-side perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,

FIG. 8 is a right-side view thereof.

The broken lines are for the purpose of illustrating portions of the article that form no part of the claim.

1 Claim, 7 Drawing Sheets
